Primary Examiner — Kelley A Donnelly*(74) Attorney, Agent, or Firm* — Hahn Loeser & Parks LLP; Daniel J. Smola(57) **CLAIM**

The ornamental design for a fabric display apparatus, as shown and described.

DESCRIPTION

FIG. 1 is a perspective view of the fabric display apparatus; FIG. 2 is a front elevational view of the fabric display apparatus of FIG. 1;

FIG. 3 is a rear elevational view of the fabric display apparatus of FIG. 1;

FIG. 4 is a right side elevational view of the fabric display apparatus of FIG. 1;

FIG. 5 is a left side elevational view of the fabric display apparatus of FIG. 1;

FIG. 6 is a top plan view of the fabric display apparatus of FIG. 1; and,

FIG. 7 is a bottom plan view of the fabric display apparatus of FIG. 1.

The broken lines in the drawings illustrate portions of the fabric display apparatus that form no part of the claimed design.

1 Claim, 4 Drawing Sheets(56)
